BANDAGE MAKING MACHINE

Hugo Frank Keller, Oneida, N. Y.

Application March 5, 1936, Serial No. 67,410

10 Claims. (Cl. 91—15)

This invention relates to a machine for making surgical bandages in which a fabric layer is supplied with a layer of plaster of paris or similar material.

5 The object of the invention is to provide a machine which can be manually operated and, particularly, manually controlled to produce a roll of bandage in an expeditious manner and of a substantially uniform thickness, which can be 10 predetermined readily by a quick adjustment of the machine.

A further object is to provide a machine wherein may be made rolled bandage whose interior is readily accessible to water when the bandage 15 is being prepared just prior to use.

With these general objects in view and some others which will be apparent to those skilled in the art from the description hereinafter, the invention consists in a bandage-making machine 20 having the features, details and combinations of parts which will first be described in connection with the accompanying drawings and then more particularly pointed out.

In the drawings,—

25 Fig. 1 is a side elevation of the machine,

Fig. 2 a front elevation of the machine with a bandage partly completed with parts of the machine and plaster broken away.

Fig. 3 a detail sectional view on the line 3—3, 30 Fig. 1.

Fig. 4 a sectional view of the arbor and part of a bandage, taken along the line 4—4, Fig. 1, but with a part of the crank broken away.

Fig. 5 a detail in perspective illustrating the 35 edge-turning device.

Fig. 6 a transverse section on the line 6—6, Fig. 4.

Fig. 7 a detail sectional view of the arbor with a part of a bandage thereon, and

40 Fig. 8 a detail in perspective illustrating a modification of the invention.

Fig. 9 is a detail view of a fabric roll spindle and collars.

Fig. 10 is a perspective view of one of the 45 collars.

Referring to the drawings, 10 is a stand which is lower at the front than at the back of the machine. Upon this stand is hinged a table 11 which has ears 12 at its front end, through each 50 of which is screw-threaded a trunnion screw 13, with a conical end arranged to enter a conical trunnion socket formed in the stand, as shown in Fig. 2. The trunnion screws are provided with notched ends and each carries a lock-nut 14. By 55 means of this hinged connection the table may be

swung upward and forward, or may lie back on the stand at a slant, as shown in Fig. 1.

The rear and higher end of the table has outward-extending ears, 15, having conical trunnion sockets. At 16 is a hopper device having a front and two sides only, that is to say, without a bottom, top, or back. The sides of this hopper device have sloping bottom edges conforming to the slope of the table, and each is provided with an outward-extending arm, having a downward-extending lug, through which is screw-threaded a trunnion screw 18 having a pointed end which enters the respective trunnion socket in the ears 15 of the table, as will be clear from Fig. 2. Each trunnion-screw 18 is provided with 15 a lock-nut 19. The hopper device is free to swing down toward the top of the table 11. It has a flange 20 extending outward on the sides and front, the inside of the hopper device at the front wall being sloped or beveled as shown in dotted lines in Fig. 1 to form a lip at the bottom of the front wall, for a purpose hereinafter explained.

The table 11 has on one side, an outward-extending boss 21, Fig. 3, into which is screwed a machine screw 22 having a head and a cylindrical portion of enlarged diameter inside the head, this being indicated at 23 in Fig. 3. On this part 23 is mounted a lever arm 24 having a cam device 25, which terminates in a substantially radial face, as shown in Fig. 1, for a purpose hereinafter explained. The flange 20 of the hopper device is provided at one side with an outward-projecting arm 26, Figs. 2 and 3, which is arranged to ride on the cam surface of the cam device 25 and carries a bearer arm 27 with a hooked end arranged to ride on the cam surface, whereby the hopper device may be raised by the cam, and, at the proper position of the cam device, to engage the radial face of the cam device and thereby prevent the lever arm 24 swinging forward again, unless the hopper device is lifted upward from the table to raise the hooked end of the bearer arm 27 out of engagement with the radial face of the cam device. The bearer arm 27 is held to the outward-projecting arm 26 in any suitable way, as for example, by two screws 28 as shown in Fig. 2. The arm 26, carried by the hopper device, is provided with an adjusting screw 29 which has a milled head and carries a spiral spring 30 which keeps a pressure on the screw to hold it in any adjusted position. The end of the screw is intended to rest on the upper surface of the table. By adjusting the screw 29, the hopper-device may be prevented from contacting with the table and

45 50 55 60 65 70 75 80 85 90 95 100

thereby its front lip may be held at any desired distance from the table, for a purpose herein-after explained.

The lever arm 24 has a handle 24a and also 5 has an enlargement extending outward to serve as a journal bearing 31, in which an arbor may be rotatably mounted.

The construction of the arbor is shown more 10 particularly in Figs. 4 and 6. Its body portion, 15 on which the bandage is to be wrapped, is cylindrical, but made in two parts, each being segmental in cross-section, as shown in Fig. 6, the angle of one segment being about 90° and that of the other segment being about 270°, it being understood that these angles are not critical. The part having the smaller angle in cross-section is indicated at 32 and the larger or main body portion of the arbor is indicated at 33. The latter may be formed with a longitudinal groove 20 as indicated at 34, Fig. 6. The space in the main body portion 33 for the reception of the smaller part 32 is made somewhat larger in cross-section than is the latter, in order to permit the end of the bandage fabric to be clamped between 25 the two parts of the arbor while at the same time preserving a substantially cylindrical contour for the complete arbor. Each part of the arbor extends beyond the other part at one end only, as shown in Fig. 4, and the extension of each 30 may be completely circular in cross-section. The smaller part 32 has its extension 35 fitted with a crank handle 36. Where the arbor portions are to be made of cast metal, the handle may be connected to the part 32 by an embedded screw 37, having a threaded portion projecting beyond the part 32, onto which the handle is screwed by turning it in the direction of rotation which it has when in operation until it abuts against the end of the part 32. By turning the crank in the 35 opposite direction it may be unscrewed and taken off.

The embedded screw 37 has a head 38 which may be suitably formed to provide recesses for entry of the molten metal of the part 32 at the 40 time of casting it. In the example illustrated the head of the screw has a plurality of circumferential grooves.

The extension of the main body portion 33 of the arbor is indicated at 39. It is provided with 45 an outward extending journal member 40 having its inner end formed to be embedded in the extension 39 of the main body portion 33 of the arbor. In the present example, the embedded end of the journal has two flanges 41, 42, with an 50 intermediate portion 43 of reduced diameter which may be knurled as indicated in Fig. 4 to insure a good hold on it of the cast metal.

The end of the extension 39 is counterbored to receive the reduced end of the journal bearing 55 31. To hold the journal 40 in its bearing, 31, and still permit rotation of the journal, a machine screw 44 is threaded into the outer end of the journal and is provided with a head 45 bearing against the end of the journal bearing 60 31.

In order to connect the two parts 32 and 33 of the arbor, while permitting them to be readily disconnected, each is provided at one end 65 with a dowel pin which enters a mating socket in the other part of the arbor. The dowel pin carried by the smaller part, 32, of the arbor is indicated at 47, and that carried by the larger part, 33, is indicated at 48, Fig. 4.

It will be apparent that the arbor as a whole 70 75 may be rotated in the journal bearing 31 carried

by the lever arm 24, by turning the crank 36. Also, that by pulling the crank bodily outward away from the machine, the smaller part 32 of the arbor may be drawn endwise to release it from the main body portion 33 which remains 5 supported by its journal 40 and the bearing 31. In this way, after a bandage has been wound on the arbor, the part 32 may be withdrawn, thereby releasing the roll of bandage so that it may readily be drawn off the main body portion 33 10 of the arbor.

At the rear of the machine a support for a spool 49, carrying a roll of bandage fabric, 50, may be provided. This support consists of a pair of hangers, one of which is visible in Fig. 1 and 15 indicated at 51, the other not being shown. Each hanger has a slot to receive the spindle 52, which passes through the axis of the spool 49.

To prepare the machine for use in making a bandage, a spool carrying a roll of bandage fabric 20 of the desired width is mounted on a spindle 52 and then put in place in the hangers in such a way that the fabric will unroll from the outside as shown in Fig. 1. The web of fabric is led up over the edge of the table 11, the hopper device 25 being swung upward on its trunnions by the cam on the lever arm to allow ready access to the top of the table when threading the web. Also, the two sides of the hopper device at the back may be rebated as indicated at 53, Fig. 1, as required, to 30 give more clearance to permit of a backward tilting of the hopper device.

When the web has been drawn to the front of the machine, its front end may be clamped in the arbor by withdrawing the part 32 from the part 33, putting the web in the recess in the latter, and then replacing the part 32. When the web of fabric has been threaded through the machine and clamped to the arbor, and with the hopper device in its normal place close to the table, the 35 adjusting screw 29 is adjusted to raise the front bottom edge or lip of the hopper device the requisite distance above the top surface of the table so as to leave a small space between the bottom of the front edge of the hopper device and the top surface of the web of bandage fabric, assuming that the latter was pressed down on the table top. The hopper device is now charged with powdered plaster of Paris, or such other powdered 40 material as is to be employed to make the bandage. The material used may have suitable ingredients to retard the setting of the bandage, if 45 desired.

When the hopper device is charged to the extent required, the crank handle 36 is turned in the direction to wind the bandage fabric 50 on the arbor and thus draw it along the top of the table 11. This causes the powdered material which rests on the fabric to be drawn out of the hopper device at the front lower edge or lip of the latter, in a layer of such thickness as was determined by the adjusting screw 29, the chamfered or inclined inner surface at the bottom of the front wall of the hopper device allowing the powdered material to feed down readily to the space beneath the front wall.

It will be found that the powdered material in the hopper device will be drawn out with the bandage fabric so as to cover the latter with a 50 layer of such powdered material equal to the width of the web of bandage fabric, and that there is no tendency of the powdered material to run out of the hopper device except where it is drawn out by the top surface of the web. The 55 60 65 70 75 80 85 90 95 98 99 100

bandage is now complete and passes to the arbor where it is wound up.

While the crank 36 is being turned and the bandage wound up, the operator may lift up 5 slightly on the lever arm 24 thereby relieving the pressure of the coil of bandage material against the table top, due to its gradually increasing weight, so that the powdered material may not be compressed as it passes under the arbor. At 10 the same time the friction of the bandage against the table top serves to determine the tension of winding, and this is determined by the operator. As the operator may use the right hand to turn the crank and the left hand to manipulate the 15 lever arm 24, he has such a control over the pressure and tension that he can wind the bandage either loosely or tightly with corresponding compression of the powdered layer.

If desired the bandage web may be cut when 20 a sufficient amount has been wound up on the arbor, most advantageously by cutting the bandage web along a line transverse to the web where it is lying on the table. The roll of bandage is removed from the arbor by first drawing out longitudinally, the smaller part 32 of the arbor. Then the roll may be tied with string and put away for future use. To continue the production 25 and winding of bandages, the end of the bandage web still lying on the table is freed of its plaster of Paris layer for a short distance back, so as to leave merely fabric at the end. This is clamped 30 between the two parts of the arbor, as hereinbefore described, and then by turning the crank, the production and winding of the bandage is 35 proceeded with as before. Sometimes it is the practice to use just a strip of bandage fabric of a length only sufficient for the bandage wanted. In this case the strip is coated and wound up on the arbor, being drawn entirely through the machine. In making a bandage in this way, it is 40 generally the case that a surplus of powdered material remains in the hopper device and, before a new strip of web can be threaded through the machine, it is necessary to empty all powdered 45 material from the hopper device. The present machine allows this to be done conveniently by latching the lever arm 24 in its erect position and then swinging the table and hopper to the position shown in dotted lines in Fig. 1. This allows 50 the hopper device to discharge its contents into some receptacle held at the front of the table. When the hopper device is emptied in this way, it, with the table, may be swung back into the 55 position for further operation. If a new web is to be threaded through the machine it can be done at this time, while the lever arm is still held in its erect position.

By then lifting up the front edge of the hopper device the catch which holds the lever arm is 60 released therefrom and the latter may be swung to its operative position.

It is sometimes desired to produce a bandage with its edges folded over. To enable this to be 65 done two cloth-turners may be provided, these being outside the hopper device and secured to the front thereof. In the present embodiment of the invention the cloth-turners, one of which is shown at 54, Fig. 5, comprise an ordinary sheet 70 metal folding foot similar to those commonly employed on the standard sewing machines, and dimensioned to fold over a sufficient margin of bandage fabric. As shown, the cloth-turner has one end bent inward to form a supporting and 75 securing flange 55 which bears against the front

of the hopper device and is secured thereto by a screw 56 passing through a slot in the flange, thus allowing for vertical adjustment of the cloth-turner. The front of the hopper device has a series of threaded holes for each cloth-turner, one series of holes 56a being illustrated in Fig. 5. The screw 56 may enter any one of the holes, so the cloth-turner may be adjusted for different standard widths of bandage. The flange 55 of said cloth-turner has its bottom edge 5 notched at the inner end, the outer part of said flange resting in contact with the fabric, while the edge of the notched part remains at a distance above the surface of the fabric, for a reason which will be explained hereinafter. 10 15

When the web of fabric has been threaded through the machine and clamped to the arbor, the cloth-turners may be secured in place, or if desired, they may be put in place, first, before the fabric is threaded through, in which case its 20 margins must be threaded through the cloth-turners and the end of the web may then be clamped to the arbor with its edges turned, or they may be unfolded and lie flat. The flange 25 55 of the cloth-turners 54 acts as a gage to determine the width of the layer of powdered material passing out of the hopper device, this width being sufficiently less than the width of the web of fabric to leave a free margin of fabric at each edge of the web. As the web leaves the hopper 30 the margins of the fabric enter the respective cloth-turners and are folded over onto the layer of powdered material, for a short distance, as will be clear from Fig. 5, where X indicates the 35 portion of the web folded over.

In using a roll of bandage, it is the practice to immerse it in water just before it is to be used, to wet the plaster of Paris, or similar material. By the ordinary method of winding a bandage as 40 herebefore described, the interior of the bandage roll is not readily accessible to the water, or, at least, care must be used to immerse the bandage roll for a time sufficient to allow the water to soak in to the interior of the roll. To avoid this delay, a modification of the invention may be 45 employed, this consisting in winding in, with the web of bandage material, a plurality of separators, which remain in the roll when immersed, to provide channels for the admission of water. When the roll is removed the separators may be 50 withdrawn from the roll. A separator which is very suitable for the purpose is indicated in Fig. 8 at Y. This is a transversely curved strip of metal with inturned edges and with an inturned outer end, y, which may serve as a finger-hold 55 in withdrawing the separator from the bandage roll. As many as desired of these separators may be applied and wound in the bandage roll, one only being shown in Fig. 8.

An important feature of the present bandage 60 machine is that the amount of machine work is reduced to a minimum while at the same time accuracy of the machine in operation is maintained. The top surface of the table is made substantially true by machining or grinding, and the trunnions of the hopper device which connect it to the table, as well as the trunnions of the table which connect it to the stand, are readily located in proper relative alignment by the use of jigs so that the web will be wound 70 evenly and will travel in a line truly at right angles to the axis of the arbor. Also on account of the adjustable conical trunnion screws and their corresponding sockets, lost motion due to wear may be taken up when necessary, there- 75

by avoiding lateral play of the hopper, table, and arbor with relation to each other and to the stand.

One very important feature of the invention is 5 that the table slopes downward toward the winding arbor and that the latter is so mounted that the web of bandage fabric will travel in close contact with the table on its way to the winding arbor and, also, the roll of bandage as it is wound 10 on the arbor may contact with the table, the amount of pressure of this contact being controlled by the operator. Hence, as the bandage is wound up the tendency to squeeze out the powdered material is overcome because of the 15 down-coming powdered material on the flat portion of the web close to the roll.

A further important feature of the invention is that the pivotal point, or journal bearing, of the lever arm is forward of the axis about which the 20 hopper device is angularly removable, and, of course, also at the rear of the axis about which the winding arbor rotates. This simplifies the control of the hopper device by the cam and at the same time avoids a heavy lever arm which 25 might tend to compress the bandage roll against the table, or tire the operator if he has too much weight to hold up while winding.

In Fig. 9 is illustrated a spindle 52a for the 30 spool of fabric which is provided with two heads or collars 52b adjustable to different positions on the spindle, these heads serving to retain the roll of fabric, 50, between them. Each head is of pressed resilient metal having a large cylindrical portion, f, a flange, g, extending therefrom 35 and a small cylindrical portion, h, having an in-turned flange, i. The small cylindrical portion, h, and its flange, i, are slotted longitudinally to serve as resilient fingers or segments.

The spindle 52a has a plurality of peripheral 40 rounded grooves located at suitable distances apart so that the heads or collars 52b may be adjusted to distances apart such that rolls of bandage fabric of different widths may be accommodated between the heads. The slotted in-turned flange, i, of a head will ride into the 45 respective grooves in the spindle and retain its head at the place to which it is set. Since the said grooves are rounded, the flange will ride out of a peripheral groove if sufficient force be applied to the head to move it from one position 50 to another.

Where a narrow roll of fabric is used it is well to keep it near one end of its spindle so that it will be wound on the outer or free end of the 55 arbor instead of near the journaled end of the arbor. This makes it somewhat easier to remove the bandage roll from the arbor.

What is claimed is:

1. In a bandage making machine, the combination, with a table having a plane upper surface, of a hopper-device located toward the rear end of the table and pivotally connected to the table along an axis transverse to the table and at the rear of the hopper-device, a winding arbor 60 rotatable about an axis parallel to the top surface of the table and over the front part thereof, a journal for said winding arbor movable toward and away from the upper surface of the table, and means for rotating said winding arbor.

70 2. In a bandage making machine, the combination, with a table pivotally mounted near its front end to swing about an axis transverse to the table and parallel to its top, a hopper-device having an open bottom, said hopper-device being 75 pivotally connected to the table along an axis

transverse to the table and at the rear of the hopper-device, a winding arbor journal arranged above the table and movable toward and from the upper surface thereof, a winding arbor mounted in said journal and rotatable about an axis parallel to the top surface of the table and over the front thereof, and means for rotating said winding arbor.

3. In a bandage making machine, the combination, with a table pivotally mounted near its front end to swing about an axis transverse to the table and parallel to its top, a hopper device having an open bottom, said hopper device being pivotally connected to the table along an axis transverse to the table and at the rear of the hopper device, a lever arm pivoted to swing about an axis transverse to the table and forward of the pivotal axis of the hopper device, a journal carried by the lever arm forward of its pivotal axis and above the table, said journal being movable toward and from the upper surface of the table, a winding arbor mounted in said journal and rotatable about an axis parallel to the top surface of the table and over the front part thereof, and means for rotating said winding arbor.

4. In a bandage making machine, the combination, with an inclined table sloping downward toward the front, a winding arbor arranged to revolve about an axis above the table and transverse to its length, said axis being parallel to the top surface of the table near its lower end, a journal device for said winding arbor, arranged to move toward and from the table, and means for rotating said winding arbor.

5. In a bandage making machine, the combination, with a table having a plane upper surface, a hopper device having an open bottom, said hopper device being located above the rear part of the table and pivotally connected to the table along a pivotal axis transverse to the table and at the rear of the hopper device, a lever arm pivoted to swing about an axis transverse to the table, parallel to the upper surface thereof and forward of the pivotal axis of the hopper device, 40 a journal carried by said lever arm forward of the pivotal axis of said lever arm, a cam device affixed to the lever arm and arranged to move the hopper device about its pivotal axis, a winding arbor rotatable in the journal about an axis 45 transverse to the table and parallel to the upper surface thereof, and means for rotating said winding arbor.

6. In a bandage making machine, the combination, with a table having a plane upper surface, said table being pivotally mounted near its front end to swing about an axis transverse to the table and parallel to its upper surface, a hopper device having an open bottom, said hopper device being located above the rear part of the table and pivotally connected to the table along a pivotal axis transverse to the table and at the rear of the hopper device, a lever arm pivoted to the table to swing about an axis transverse to the table, parallel to the upper surface 65 thereof and forward of the pivotal axis of the hopper device, a journal carried by said lever arm forward of the pivotal axis of said lever arm, a cam device affixed to the lever arm and arranged to move the hopper device about its pivotal axis, a winding arbor rotatable in the journal about an axis transverse to the table and parallel to the upper surface thereof, means for detachably locking the lever arm to the hopper device, and means for rotating said winding arbor.

7. In a bandage machine, the combination, with a table pivotally mounted near its front end to swing about an axis transverse to the table and parallel to its top, a hopper-device having an open bottom and located above the rear part of the table, said hopper-device being pivotally connected to the table, the pivotal axis being transverse to the table and at the rear of the hopper-device, a lever-arm fulcrumed on the table to swing about an axis transverse to the table and forward of the pivotal axis of the hopper-device, a journal carried by the lever-arm forward of its pivotal axis, above the table and forward of the hopper-device, a cam actuated by the lever-arm, and arranged to lift and lower the front end of the hopper-device, means for detachably locking the lever-arm to the hopper-device, a winding arbor mounted in said journal and extending across and over the front end of the table, said winding arbor being rotatable in the journal about an axis parallel to the top surface of the table, and means for rotating said winding arbor.

8. In a bandage making machine, the combination, with a base higher at its rear than at its front, a table having a plane upper surface, said table being pivoted at its front part to the front of the stand and normally resting on said base at an incline sloping downward from the back to the front, a fabric roll supporting device secured to the back of the base, to hold a roll of bandage fabric with its top surface not higher than the rear edge of the upper surface of the table, whereby fabric from said roll may be led over and in close contact with the table top, a hopper-device pivotally connected at its rear to the table and arranged to discharge pulverulent material onto the bandage cloth, means for adjusting the angular position of the hopper-device

with relation to the table top, a winding arbor extending transversely of and above the table in front of the hopper-device, and mounted to move toward or from the top of the table, said winding arbor being arranged to wind up the bandage fabric and draw it along and over the table top in close contact with the same, and means for rotating said winding arbor.

9. In a bandage making machine, the combination, with a table having a plane upper surface, of a hopper-device located toward the rear end of the table and pivotally connected to the table along an axis transverse to the table and at the rear of the hopper-device, a winding arbor rotatable about an axis parallel to the top surface of the table and over the front part thereof, a journal for said winding arbor movable toward and away from the upper surface of the table, and a pair of margin folding devices secured in front of the hopper-device and arranged to fold over the margin of the bandage fabric on its way to the winding arbor.

10. In a bandage making machine, the combination, with a table having a plane upper surface, and a hopper-device located toward the rear of the table and pivotally connected to the table to swing along an axis transverse to the table and at the rear of the hopper-device, of a journal, means for supporting the journal over the table in front of the hopper-device to allow it freedom of movement toward and from the top of the table, a winding arbor comprising two overlapping parts, one of which is rotatably mounted in said journal, the said parts being connected detachably by mortises and tenons to allow the parts to be separated in the direction of the axis of rotation of the arbor, and means for rotating the winding arbor.

HUGO FRANK KELLER.
